UNITED STATES PATENT OFFICE.

JAMES T. COWLEY, OF BALTIMORE, MARYLAND, ASSIGNOR TO MILTON CLARK, OF NEW YORK, N. Y.

STORE-SERVICE APPARATUS.

SPECIFICATION forming part of Letters Patent No. 315,739, dated April 14, 1885.

Application filed March 17, 1885. (No model.)

To all whom it may concern:

Be it known that I, JAMES T. COWLEY, of Baltimore, in the county of Baltimore and State of Maryland, have invented certain new and useful Improvements in Store-Service Systems; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention has for its object in providing means at the ends of each track, first, for elevating the car at the salesman's end by a flexible medium and placing it upon a switch or side track, from which it descends, and is then caused to run upon or be transferred to the incline forwarding-track, traveling to its terminal by its own gravity; secondly, in means for receiving the car on its arrival at the cashier's end of the same track by a combined rigid and flexible drop or lowering device of varying diameter; thirdly, in means for holding the car after it is detached and before its return at the cashier's end of the return-track, which track is inclined toward the salesman's station. This retaining device may either be rigid or flexible, the car remaining in position until released and started down the return track to the salesman's; fourthly, in means at the salesman's end of the return-track for receiving the car upon rigid or flexible drop or lowering mechanism of varying diameter, my said invention being thus distinguished from store-service systems which have one main forwarding-track for a number of salesmen's stations, and one main return-track for the same number of salesmen's stations; and it is also distinguished from the arresting-stops and restorers patented to Clark and Cowley, and from the aerial railways heretofore well known. I therefore desire to limit my invention to the novelty and difference existing between the various means above enumerated and the system and construction of parts, substantially shown.

My invention consists, first, in arranging two wire tracks inclined in opposite direc-

tions. Each salesman's station in the store-service system for these tracks is provided with receiving, restoring, and retaining brackets at the ends of each track. Said brackets are also provided with means for operating the drop mechanism.

The invention further consists in the novel construction of the receiving and restoring mechanism, and in the peculiar arrangement of the brackets with relation to each other and the supports, and with the cars and the automatic mechanism for preparing the restoring-drop for the reception of the car, all of which will be hereinafter more fully described.

In the drawings hereto annexed for the better illustration of my invention, Figure 1 shows a side elevation of my improved system as applied to a single station and cashier's desk; Fig. 2, a top plan view of the system applied, clearly showing the switch-brackets which throw the car from the rear of the support to the front. In considering Fig. 1, let it be remembered that the two inclined ways are substantially on the same vertical plane, except immediately over the brackets, hence only one set is seen in the plan. Fig. 3 is a detached view of the variable-sized restoring device at the cashier's end. Fig. 4 is the variable-sized restoring device at the salesman's end, one portion being attached to the supporting-post and the other passing over a pulley in a bracket extending from said post, and secured thereto above the forwarding-line. Fig. 5 shows the salesman's receiving end of the wireway, which is in close proximity to the restorer, so that the salesman can readily detach the car out of the way of the next incoming car. When the car is loaded, it can be readily hung on the restorer, which is always in readiness for its reception, by means of the weight automatically pulling it down after the car is delivered to switch and track. Fig. 6 shows the retaining device to be used at the cashier's end when it is desired to retain the car for any purpose, and Fig. 7 is a plan view of the restoring switch-post and bracket. Fig. 8 is a side elevation of the car I propose to use in connection with my store-service system; and Fig. 9 is an end view, partly in section and partly in elevation, which

shows the traveling space of the car to be longer than the inlet thereto, whereby when the car comes to the receiver or drop, the said drop being larger than the wireway, the car 5 cannot leave it.

As illustrated in the drawings, the two tracks A and B are shown as converging toward each other at one end, preferably the cashier's end C. These tracks are the same as shown in 10 Knight's mechanical dictionary; but in my invention the two tracks are supported at their ends by the above-described brackets *a b*, and form a connection to and receive the rigid or flexible drop-receiver D and restorer E, the 15 operation being as follows: The restorer E, at the salesman's end of the forwarding-track, is always kept down within an easy reach of the sales person by a weight, *c*, and pulley *d*. The sales person makes a sale, and places the goods 20 and money in the car E. The car is then placed upon the restorer. The operator then pulls down on the loose end *f* of the restorer, the car travels up the flexible restorer and passes off onto the side switch-track, G, thence 25 onto the forwarding-track A, to the receiver H at the cashier's station. The car is then unloaded, the goods wrapped, and change made, when the car is again loaded and ready to be returned. It is then taken by hand from its 30 resting-place in the receiver H and placed upon the retainer I on the return-track. It is then gently pushed out of the retainer and travels down the return-track and into the receiver D, where it is lowered to within easy reach 35 of the sales person. The car is then taken off from the receiver of the return-track. The weighted handle *i* then carries the receiver up to place again. The car is then unloaded and placed in the restorer E, to remain until used 40 again.

In the practical working of my new wireway system I find it preferable to use a cord or rope drop or elevator. One of the important features of the flexible drop or elevator is to provide means whereby the car 45 cannot in any possible way jump off or leave the terminal brackets, or get off of the drop or elevator until taken off by hand. This is effectually provided for by using a rope that 50 is very much larger at the end and fastened to the bracket and then tapering down to the resting portion. The car is so constructed as to be operated upon said drop so that it will be impossible for it to be taken off until it has 55 nearly reached the smallest portion of the drop. I use the same flexible drop as above described for both receiver and restorer. It is not so essential to have a flexible drop, as above described, at the cashier's end of the 60 forwarding-track as at the salesman's end, as the weight always keeps it in place, while at the salesman's end the sales person is liable to misplace the drop or allow it to get caught on the shelves and counters, allows the receiver to become slack or loose, and thus 65 causes the car to fall if the rope drop is too

small for it to pass off. The degree of inclination necessary for the perfect traveling of the cars may be determined by raising the brackets up or down on the supporting-post, and 70 when so determined the bracket is rigidly fixed to the post by means of the set-screw.

Having described my invention, what I claim is—

1. In a store-service apparatus, the combination, with the wireway, of a lowering and raising device pivotally fixed to the bracket, 75 the flexible portion thereof being of varying diameter, the thicker portion to prevent the car from leaving the drop, while the thinner portion permits the removal thereof, substantially as described.

2. In a store-service apparatus, the combination of a wireway, and a lowering and raising device, the flexible portion of which is of 85 varying diameter, with a car attachment for retaining the car to the larger portion of said device, and to permit its removal from the smaller portion thereof, substantially as set forth.

3. In a store-service apparatus, the combination, with the wireway, of a support having 95 an adjustable bracket to which the way is fixed, and a bracket extending in opposite direction from the way, in combination with the variable-sized flexible drop, substantially as described.

4. In a store-service apparatus, the combination of the double-incline ways with a sustaining-support having a lowering device on 100 one side and an elevating device on the other side of said post, and with a switch for receiving the car and carrying it around to the track in front of said support, substantially as set forth and described.

5. A store-service apparatus consisting of 105 wireways having flexible lowering and raising devices, the latter having a weight and a car on the flexible portion, whereby the weight will automatically lower the drop after the car has left it for the reception of the next car, substantially as described.

6. In a store-service apparatus, the carrying-wires arranged in pairs, inclined in opposite directions, but converging to the cashier's 115 desk, said wires being rigidly fixed at each end and connected to brackets which are adjustably secured to the sustaining-posts, in combination with the drop mechanism to each wire for raising and lowering the cars, substantially as described.

7. In a store-service apparatus, the carrying-wires arranged in pairs, each being inclined to carry a car in opposite directions, 125 said wires being connected by brackets which are adjustably fixed to the sustaining-posts, in combination with a car lowering and raising device, the flexible portion of said device being variable in diameter, substantially as set forth.

8. In combination with the forwarding and return wire tracks extending in pairs between 130

the cashier's desk and a salesman's station, | the brackets, receivers, and restorers at the ends of each track, substantially as shown.

9. The combination, in the store-service apparatus, of the wire tracks rigidly fixed at each end, the flexible receivers, and flexible restorers, with the side track or switch, and the car or carrier, substantially as described.

In testimony that I claim the foregoing as my own I affix my signature in presence of two witnesses.

JAS. T. COWLEY.
